United States Patent

Des. 234,895
Patented Apr. 15, 1975

234,895

FRAME

Joseph Bezborodko, 629 Kappok St.,
New York, N.Y. 10463

Filed Feb. 22, 1973, Ser. No. 334,966

Term of patent 14 years

Int. Cl. D6—07

U.S. Cl. D6—242

FIG. 1

FIG. 2

FIG. 3

FIG. 1 is a top perspective view of a frame showing my new design, a portion of each side being broken away to indicate indeterminate length;

FIG. 2 is a top perspective view of a second embodiment of a frame showing my new design, a portion of each side being broken away to indicate indeterminate length; and

FIG. 3 is a fragmentary perspective view of the frame shown in FIG. 1.

I claim:

The ornamental design for a frame, substantially as shown.
